UNITED STATES PATENT OFFICE.

VICTOR W. PAGE, OF NEW YORK, N. Y.

CRANK-CASE CONSTRUCTION

Application filed April 15, 1921. Serial No. 461,713

To all whom it may concern:

Be it known that I, VICTOR W. PAGE, a citizen of the United States, and a resident of the city of New York, Kew Gardens, borough of Queens, in the county of Queens and State of New York, have invented a new and Improved Crank-Case Construction, of which the following is a full, clear, and exact description.

10 The present invention relates to new and useful improvements in motors and it pertains particularly to a new and novel construction of crank cases therefor. Crank cases as commonly constructed have a drain
15 outlet disposed centrally of the bottom wall thereof and said outlet is generally closed by means of a screw plug. In constructions of this character it is necessary to get beneath the motor to remove the screw plug
20 in order that the crank case may be drained, which operation is attendant by various disadvantages.

It is one of the objects of the present invention to provide a crank case for motors in which the drain is not centrally disposed with respect to the bottom wall thereof.

It is a further object of the invention to provide a new and novel means for closing the drain opening.

30 It is a further object of the invention to provide controlling means for the drain opening which controlling means is capable of operation from above the motor rather than below the same as is the common practice.

With the above and other objects in view, reference is had to the accompanying drawings, in which

40 Figure 1 is a transverse sectional view of a motor crank case showing the invention applied thereto.

Fig. 2 is a view in elevation of the complete closure member.

Referring more particularly to the drawings, the reference character 5 designates the crank case, the crank shaft and bearings being designated by the reference characters 6 and 7, respectively. The reference character 8 designates the drain opening and said drain opening is positioned near one of the lower edges of the crank case in a position where all of the contents of the crank case will drain towards said opening.

55 Depending from the lower wall of the crank case is an integral nipple or the like

9 provided with a central passage 10 and the upper end of said passage 10 is tapered to provide a seat 11. The reference character 15 designates a housing mounted interiorly of the crank case 5, and said housing is adapted to have its upper end closed by means of a screw-threaded plug or the like 16, which plug 16 is provided with a central opening or passage 17.

The lower wall of the housing 15 is provided with an opening or passage 18, and mounted for sliding movement in said passage or opening 18, is a plug 19. This plug has its lower end tapered as indicated by the reference character 20 and said tapered portion is adapted to seat or engage the tapered portion 11 of the passage 10 in order to close the drain opening 8 in the bottom wall of the crank case. The plug 19 is provided with a reduced extension 21 and said reduced extension has its upper end bifurcated as at 22. The reduced extension of the plug 19 is slidably mounted in the passage or opening 17 of the screw-threaded member 16 in order to provide an upper guide for the plug 19. Interposed between the upper end of the plug 19 and the inner face of the screw-threaded member 16 and surrounding the lower portion of the reduced portion 12, is a coil spring 23, and said coil spring exerts a pressure downwardly sufficient to maintain the tapered end of the plug in engagement with the seat 11 of the passage 10 in order to provide an effective closure for the drain opening 8.

The device operates in the following manner: 105

Assuming that the crank case has the usual amount of oil therein, and it is desired to drain the same, the handle 26 is grasped and the hook 27 is disengaged from that lug 28 with which it is engaged. Upon

an upward pull on the handle 26, the tapered portion 20 of the plug 19 will be disengaged from the seat 11 of the drain opening, thus permitting the oil to flow from the crank case. It is to be understood that this drain opening will be left open just so long as the hook portion 27 of the handle 26 is engaged with one of the lugs 28. When it is desired to close the drain opening, the hook 27 and the handle 26 are disengaged from that lug with which they are engaged, and under the influence of the spring 23, the tapered portion 20 of the plug 19 will be moved into engagement with the seat 11 of the drain opening 8.

From the foregoing it is apparent that the present invention provides a new and novel controlling mechanism for opening and closing the drain of the crank case, and, at the same time, said operating mechanism is so positioned with respect to the motor crank case that it is not necessary to get

beneath the motor to open the crank case drain.

I claim:

In a crank case having a discharge opening, a chamber formed on one of the side walls of the crank case and positioned interiorly thereof, a tapered plug having a reduced extension, said tapered plug being slidably mounted in the bottom wall of said interior chamber, a coil spring surrounding the reduced extension of the tapered plug and serving to maintain the tapered plug in position in the discharge opening of the crank case, means exterior of the crank case for operating said tapered plug to remove the same from the drain opening of the crank case, and means for maintaining said tapered plug out of engagement with said drain opening against the action of said coil spring.

VICTOR W. PAGE.
